Belisario & Nadel LLP(57) **CLAIM**

The ornamental design for a handle grip for control lever, as shown and described.

DESCRIPTION

FIG. 1 is a front and top perspective view of a handle grip for control lever in accordance with my new design;

FIG. 2 is a top view thereof;

FIG. 3 is a bottom view thereof;

FIG. 4 is a front view thereof;

FIG. 5 is a rear view thereof;

FIG. 6 is a right side elevational view thereof; and,

FIG. 7 is a left side elevational view thereof.

The broken lines in the figures are directed to environment and are for illustrative purposes only; the broken lines form no part of the claimed design.

1 Claim, 4 Drawing Sheets---
